UNITED STATES PATENT OFFICE

117,417

DESIGN FOR AN ELECTRIC FENCE CONTROLLER

Clifford E. Ives, Chicago, Ill.

Application September 16, 1939, Serial No. 87,252

Term of patent 3½ years

To all whom it may concern:

Be it known that I, Clifford E. Ives, a citizen of the United States, residing at Chicago, in the county of Cook and State of Illinois, have invented a new, original, and ornamental Design for an Electric Fence Controller, of which the following is a specification, reference being had to the accompanying drawing, forming part thereof.

The single figure in the drawing is a perspective view of an electric fence controller showing my new design.

The rear portion of the controller (not shown) is identical in appearance to that of the front.

I claim:

The ornamental design for an electric fence controller, as shown and described.

CLIFFORD E. IVES.
